UNITED STATES PATENT OFFICE.

SENECA MORRIS PIKE, OF TROY, NEW YORK, ASSIGNOR TO WILDER-PIKE THERMOMETER CO., INC., OF TROY, NEW YORK, A CORPORATION OF NEW YORK.

THERMOMETER.

Application filed July 12, 1922. Serial No. 574,428.

To all whom it may concern:

Be it known that I, SENECA MORRIS PIKE, a citizen of the United States, residing at Troy, in the county of Rensselaer and State 5 of New York, have invented new and useful Improvements in Thermometers, of which the following is a specification.

Reference may be had to the accompanying drawings, and the reference characters 10 marked thereon, which form a part of this specification. Similar characters refer to similar parts in the several figures therein.

The principal object of the invention is to protect the liquid-containing tube of the 15 thermometer, and provide means for detachably mounting the thermometer upon a rod or the like, such as one of the bars of an oven shelf.

Other objects will appear in connection 20 with the following description.

Fig. 1 of the drawings is a view in front elevation of a thermometer made in accordance with my invention.

Fig. 2 is a side view of the same mounted 25 upon a supporting rod.

Fig. 3 is a cross section of the same taken on the broken line 3—3 in Fig. 1.

Referring to the drawings wherein the invention is shown in preferred form, 1 is a 30 liquid-containing tube terminating at the lower end in a bulb, 2, containing mercury or the like suitable for thermometric use.

The tube is mounted upon a channeled frame, 3, within the channel in the frame in 35 position to be protected by the side walls, 4, of the frame, the tube being thus mounted in the usual manner by wire straps or clips, 5.

Attached to the lower end of the frame, 3, is an L-shaped bracket, 6, the lower end 40 of which forms a horizontal flange, 7, which extends opposite the lower end of the channel in the frame, 3, and opposite the bulb-tube, 1, in position to protect the bulb-end of the tube.

The side walls, 4, of the channeled frame, 3, are tapered upwardly from their lower ends wherat they are of sufficient width to properly protect the bulb-end of the tube 1.

The lower ends of the side walls, 4, are 50 formed with alined notches, 8, adapted to engage a rod, 9, or the like, which rod may be a rod of an oven shelf such as is commonly used in the ovens of gas stoves and the like.

The horizontal flange, 7, of the bracket, 55 6, is provided with a screw-threaded aperture, 10, adapted to receive a screw, 11, in position for the screw to engage the rod, 9, seated in the notches, 8, whereby the thermometer frame can be securely attached to said rod, 9.

The rod-engaging end of the screw, 11, is preferably provided with an enlargement or head, 12, to engage the rod, 9. 60

By unscrewing the screw, 11, the thermometer frame can readily be released and detached from the rod, 9, when the use of the thermometer in the oven is not desired. 65

The device is readily applied to the rod, 9, by merely setting the notched ends of the side walls, 4, of the frame upon the rod and then setting up the screw, 11, to securely clamp the rod. 65

The widening of the side walls, 4, in the 70 lower end to protect the bulb-end of the tube, 1, makes said walls of sufficient width to provide for the forming of the notches, 8.

The frame, 3, and bracket, 6, are preferably struck up from sheet-metal, but may 75 be made of any suitable material adapted to withstand oven temperatures.

What I claim as new and desire to secure by Letters Patent is:

1. A thermometer having a liquid-containing tube mounted within a channeled frame formed with alined notches in its side walls at one end, and screw mechanism mounted upon the frame in position to engage a rod seated in said end notches in the 80 side walls of the frame. 85

2. A thermometer having a liquid-containing bulb-ended tube mounted within a channeled frame having side walls on opposite sides of said bulb of sufficient width 90 to protect the bulb, said side walls being formed with alined notches in the ends adjacent to said bulb, and having a flange offset from the frame opposite the bulb-end of the tube, said flange being provided with a screw-threaded aperture, and a clamping screw fitting the screw-threaded aperture in said flange in position to engage a rod seated in said end notches in the side walls 95 of the frame. 100

In testimony whereof, I have hereunto set my hand this 7th day of April, 1922.

SENECA MORRIS PIKE.
